CLAIM

We claim the ornamental design for an aerosol generator, as shown and described.

DESCRIPTION

FIG. 1 is a top front perspective view of an aerosol generator.

FIG. 2 is a bottom rear perspective view of the aerosol generator depicted in FIG. 1.

FIG. 3 is a front view of the aerosol generator depicted in FIG. 1.

FIG. 4 is a rear view of the aerosol generator depicted in FIG. 1.

FIG. 5 is a left side view of the aerosol generator depicted in FIG. 1.

FIG. 6 is a right side view of the aerosol generator depicted in FIG. 1; and,

FIG. 7 is a top view of the aerosol generator depicted in FIG. 1.

The broken lines in the drawings illustrate portions of the aerosol generator that form no part of the claimed design.
